UNITED STATES PATENT OFFICE.

IRVIN M. KELLEY, OF LACONIA, NEW HAMPSHIRE.

KNITTING MACHINE.

Application filed September 17, 1921. Serial No. 501,387.

To all whom it may concern:

Be it known that I, IRVIN M. KELLEY, a citizen of the United States, residing at Laconia, in the county of Belknap, State of New Hampshire, have invented a certain new and useful Improvement in Knitting Machines, of which the following is a specification, reference being had therein to the accompanying drawings.

10 The invention is an improvement in knitting machines of the constructional type having two needle-beds or carriers arranged edge to edge, with the needle-receiving grooves or tricks of each thereof registering 15 or alining with those of the other; and having also double-ended needles which are transferable from one needle-bed or carrier to the other thereof by being moved lengthwise out of the grooves of the former 20 into those of the latter, so that the stems thereof slide through the loops which encircle them, such loops remaining engaged with the said needles in readiness for continuance of the knitting. The transferal produces in 25 the fabric being knit in a machine of such type variations due to the fact that while a double-ended needle is in operation in one bed or carrier, the needle-end which at such time is in action draws to one face of the 30 fabric each loop that is formed by such needle, while after the needle has been transferred to the other bed or carrier, and while it is in operation in the latter, the other end of the needle is in action and each loop 35 formed thereby is drawn to the opposite face of the fabric.

Heretofore, in usual practice, the double-ended needles of machines of the type in question have been unprovided with cam-butts or heels, to be engaged by actuating cams as usual in the case of the needles of other types of machines employing needles which are independently moved endwise for the purpose of knitting. Instead, they are 45 actuated to knit by means of jacks which engage with the hooked ends of the needles, such jacks being engaged by the cams of the machine and being reciprocated thereby, and in turn acting through their engagement 50 with said hooked ends to reciprocate the double-ended needles for knitting. It has not been practicable to provide double-ended needles with butts or heels, because the latter would catch against the loops upon the 55 stems of the needles, in the endwise movement of the needles through such loops at

the time of being transferred from one needle-bed or carrier to the other.

The general object of the present invention is to render it feasible and practicable to 60 furnish the double-ended needles of the said machines with butts or heels, and to actuate such needles directly by the knitting cams through the engagement of the latter with such butts or heels.

65 I accomplish this general object by combining with double-ended needles having cam-butts or heels, means for lifting over the said butts or heels knitting loops which surround the needle-stems. In the case of 70 the preferred mode of carrying the invention into effect I combine with the needles latch-members which are movable into position to lift and spread and guide the loops over the butts or heels, so that the latter will 75 pass through such loops without catching the same.

80 The invention is applicable to either circular or straight machines.

An illustrative embodiment of the invention is shown in the drawings, in which latter,—

85 Fig. 1 is a view showing in vertical section the cylinders of a two cylinder circular knitting machine having such embodiment applied thereto.

90 Fig. 2 shows the cam-cylinders of Fig. 1 developed in a plane, and represents certain of the cams thereof as hereinafter mentioned.

95 Fig. 3 shows separately on a larger scale than Figs. 1 and 2 a double-ended needle like that shown in working position in Fig. 1.

Figs. 4 and 4^a show separately two of the 95 single-ended needles that are used with the lower cylinder.

Fig. 5 is a view of one of the jacks used with the upper cylinder for controlling the double-ended needles.

Figs. 6 and 6^a show jacks used with the lower cylinder for controlling the needles 100 of Figs. 4 and 4^a.

Having reference to the drawings,—

The upper and lower cylindrical needle-beds or carriers 1, 1^a, and cam-cylinders 2, 2^a, may in general be constructed, mounted, 105 and actuated to produce relative rotary movement between the former and the latter, as preferred in practice.

The double-ended needle 3 represented in Figs. 1 and 3 has, as usual, hooks 3^a, 3^b, at its 110 respective ends, and hinged latches 3^c, 3^d, in connection with such hooks. The interme-

diate cam-butt or heel with which I furnish the said needle is marked *a*, and at *b* is the coacting latch. The latter in this particular instance is pivoted to the needle-stem adjacent 5 the said butt or heel, to cooperate therewith, in accordance with the invention. Other loop-lifting means, as for example some other known form of movable latch, may be employed instead of a hinged latch, 10 if preferred.

The respective needle-beds or carriers 1, 1^a, are furnished with knitting cams suitable 15 for engaging with the cam-butts *a* of the double-ended needles so that the latter will be operated to knit when they occupy grooves or tricks of the upper bed or carrier, as well as when they occupy grooves or 20 tricks of the lower one. Such cams and the cam-cylinders, etc., are required to be of a construction, etc., permitting the said needles to be moved from the upper bed or cylinder down to the lower one, or from the lower one up to the upper one. Knitting cams of conventional character are represented at 4 and 25 4^a, 4^b and 4^c, in Fig. 2. The special construction, character, etc., thereof may be varied in practice to suit requirements, etc. In Fig. 2 the upper cylindrical cam-carrier 2 is provided, alongside the knitting cams 4, 30 4^a, with a continuous shoulder or race 4^d constituting a stop for the butts or heels *a* which limits the upward movement of the needles except where the latter are raised by the needle-raising cam 4, and also constituting a 35 guide for the needles between the discharging point of the said cam 4 and the engaging point thereof. Also, the lower cylindrical cam-carrier 2^a is provided, alongside the knitting cams 4^b, 4^c, with a like continuous 40 shoulder or race 4^e. Intermediate the disengaging points and discharging points of the knitting cams of the upper and lower cam-carriers, respectively, the construction permits the double-ended needles to be 45 shifted down or up, as the case may be, from one needle-bed or carrier to the other.

While a double-ended needle occupies a needle-groove or trick in the upper needle-bed or carrier the latch *b* cooperating with 50 the butt or heel *a* hangs down away from the said butt or heel, as in full lines in Figs. 1 and 3. When such needle is moved down from the upper needle-bed or carrier toward the lower one, the loop held by the lower 55 hook 3^b opens latch 3^d and closes latch *b* over upon the top of the heel or butt *a*, as indicated in Fig. 3 in dotted lines, so that as the needle slides down through the said loop the latter is expanded and raised to 60 permit the heel or butt *a* to pass therethrough.

The double-ended needles may be moved from one needle-bed or carrier to the other by hand, or known automatic means for 65 transferring them may be employed. I have

shown a mechanical arrangement which I have devised for the purpose, comprising jacks 5 in the needle-grooves or tricks of the upper needle-bed or carrier, and jacks 6, 6^a, in the corresponding grooves or tricks of the lower needle-bed or carrier. 70

The jacks 5 of the upper needle-bed or carrier have butts or heels 5^a, and the upper cam-carrier 2 has a straight groove or way 7 in which said butts or heels normally remain, and a cam-way 7^a in which they travel for the actuation of such jacks and by which the latter are moved downward at the desired time to push the double-ended needles downward from the upper needle-bed or carrier into 80 the lower one, far enough to place their butts or heels *a* close to ledge or way 4^e and within the range of action of the knitting cams of the lower cam-carrier. Following this action of the jacks in transferring the double-ended needles to the lower needle-bed or carrier, the ascending portion of cam-way 7^a raises the jacks until their butts or heels 5^a reenter the straight groove or way 7. To 85 keep the jacks in their elevated normal position until they are depressed therefrom to transfer the double-ended needles downward, each jack 5 has a rounded projection 5^b upon its upper end and a ring-shaped spiral spring 8 encircles the upper needle-bed or carrier and the upper portions of the series of jacks 5. In the elevated position 90 of a jack, the spring engages with it just below the projection 5^b, and through its action against the said projection prevents 95 descent of the jack until sufficient force to cause the projection to expand the spring and pass it is exerted, either by hand or by the cam provided to depress the jack. When 100 the jack is pushed upward again, the projection slips past the spring until the projection is above the latter.

The jacks 6, 6^a, of the lower needle-bed or carrier have butts or heels 6^a, 6^b and the lower cam-carrier 2^a has a straight groove 110 or way 9 in which said butts or heels normally remain, and a cam-way 9^a in which the butts or heels 6^a travel for the actuation of the jacks 6 and by which the latter are moved upward to push the double-ended needles upward from the lower needle-bed or carrier into the upper one, and far enough to place their butts or heels *a* close to the shoulder or guide 4^e and within the range 115 of action of the knitting cams of the upper cam-carrier. The cam-way 9^a also comprises a descending portion by which the jacks 6 are moved downward until their butts or heels 6^a reenter the straight groove or way 9. 120

It is intended that the jack-butts or heels shall not enter the cam-ways 7^a and 9^a except when the transfer of the double-ended needles from one needle-bed or carrier to the other is required to take place. Normally, 130

therefore, they occupy the straight ways 7 and 9, without being deflected therefrom by the cam-ways 7^a, 9^a. In order to cause the butts or heels of the upper series of jacks 5 to enter the cam-way 7^a when it is required to actuate the said jacks to transfer the double-ended needles from the upper needle-bed or carrier to the lower one, I provide a movable switch-cam 10, Fig. 2, at the entrance to cam-way 7^a. This switch-cam occupies normally an inoperative position, clear of the straight way 7, so that it permits the butts or heels 5^a to remain within said straight way. When, however, the said transfer of the double-ended needles is required to occur, the said switch-cam is moved into a position intersecting the straight way, and then acts upon the butts or heels 5^a to deflect them into the cam-way 7^a, whereby the jacks 5 are actuated to move the said needles down into the lower needle-bed or carrier. Similarly, a movable switch-cam 10^a, Fig. 2, is provided at the entrance to cam-way 9^a of the lower cam-carrier 2^a, 25 for the purpose of causing the butts or heels 6^a, 6^b, of the jacks 6 to enter the cam-way 9^a when it is required to actuate the said jacks to transfer the double-ended needles from the lower needle-bed or carrier to the upper one.

For some work, all of the needles employed in a machine may be double-ended needles provided with intermediate heels or butts, and with movable latches cooperating with such heels or butts. For work in which a length of rib-knitting is succeeded by a length of plain knitting, the work may be begun with needles of such equipment in the upper needle-bed or carrier, and ordinary single-ended needles like that shown at 11, 11^x, Fig. 4, in the lower bed or carrier, alternating in the respective needle-beds or carriers in the order required by the particular kind of rib sought to be produced. After the required length of rib-knitting has been produced, the transfer of the double-ended needles from the upper needle-bed or carrier to the lower one will provide for plain knitting in continuation of the rib-knitting.

For the production of stockings having narrowings and widenings, as for heels and toes, etc., the machine may be constructed with suitable provisions therefor, including means for throwing out of action the needles which are inactive during the narrowing and widening, and for rendering the other needles successively inactive for the narrowing and active for the widening. As one means of throwing out of action the needles which are inactive during the narrowing and widening, I have shown the lower cam-carrier as having in communication with the straight way 9 a second cam-path 12 and a movable selective switch-cam 12^a in connection therewith. This selective switch-cam

12^a is farther from the surface of the lower needle-bed or carrier than the switch-cam 10^a coacting with the main cam-path 9^a. The needles 11 which are to remain in operation for the whole or a part of the time while narrowing and widening are being effected are provided with short butts 11^a which do not project from the lower needle-bed or carrier far enough to be engaged by switch-cam 12^a when the latter is moved from its inoperative position shown in Fig. 2 to its operative position, and likewise the jacks 6 of the double-ended needles which are similarly to continue in operation are provided with short butts 6^a. The single-ended needles 11^x of the group which is required to be raised en masse, and the jacks 6^x of the double-ended needles which also are embraced in such group, are provided with selective butts, i. e., longer butts or heels 11^y and 6^y that are adapted to be engaged by the said switch-cam 12^a.

In some instances, as for example when producing close or fine work with short loops or stitches, I contemplate making or forming a slack course in order to facilitate the passage of the butts or heels *a* of the double-ended needles through the loops which surround their stems, during the transferal of the said needles from one cylinder to the other. To this end, any of the usual modes of making adjustment of the stitch length may be adopted. I have shown as a conventional means for the purpose a stitch cam 4 which is vertically adjustable, it having a stem or stud 4^c which extends out through a vertical slot 4^g in cam-cylinder 2 to the exterior of the said cam-cylinder, where it is adapted to be acted upon by any convenient means for effecting adjustment of the cam or fixing its position. A like slot 41^g is shown in the lower cam-cylinder 2^a, adjacent cam 4^b, and the latter cam is shown provided with a like stud 41^c extending through said slot 41^g to the exterior of such cam-cylinder, where it is accessible for the purpose of effecting adjustment of cam 4^b to vary the length of the loops or stitches drawn thereby.

As will be apparent to those skilled in the art, some of the features of the invention are applicable in the case of machines in which the needle-grooves or tricks of one bed or carrier alternate with those of the other, in which case instead of moving the needles straightwise from the grooves or tricks of one bed or carrier into registering grooves or tricks of the other they will have to be shifted or transferred otherwise into the disaligned grooves or tricks. Also, some of the features may be applied in the case of knitting machines having the needle-beds or carriers disposed at an angle with each other, as in various known types of circular and straight machines.

What is claimed as the invention is.—

1. A knitting machine comprising two needle-beds or carriers disposed edge to edge with their needle-receiving grooves or tricks registering or alining to enable needles to be transferred by movement endwise from one bed or carrier to the other, cams in connection with each bed or carrier for actuating the needles therein to knit, double-ended needles movable from the grooves or tricks of one bed or carrier to those of the other and having cam-butts or heels adapted to be engaged by the said cams to actuate the needles to knit when in the respective beds or carriers, and means for lifting over the said butts or heels knitting loops which surround the needle-stems, so as to permit the butts or heels to pass through such loops in the endwise transferal of the needles from one bed or carrier to the other.
2. A knitting machine comprising two needle-beds or carriers disposed edge to edge with their needle-receiving grooves or tricks registering or alining to enable needles to be transferred by movement endwise from one bed or carrier to the other, cams in connection with each bed or carrier for actuating the needles therein to knit, double-ended needles movable from the grooves or tricks of one bed or carrier to those of the other and having cam-butts or heels adapted to be engaged by the said cams to actuate the needles to knit when in the respective beds or carriers, and latches movably combined with the said needles for lifting over the said butts or heels knitting loops which surround the needle-stems, so as to permit the butts or heels to pass through such loops in the endwise transferal of the needles from one bed or carrier to the other.
3. A knitting machine comprising two needle-beds or carriers disposed edge to edge with their needle-receiving grooves or tricks registering or alining to enable needles to be transferred by movement endwise from one bed or carrier to the other, cams in connection with each bed or carrier for actuating the needles therein to knit, double-ended needles movable from the grooves or tricks of one bed or carrier to those of the other and having cam-butts or heels adapted to be engaged by the said cams to actuate the needles to knit when in the respective beds or carriers, and latches hinged to the needles and adapted to swing over the said butts or heels so as to permit the latter to pass through knitting loops surrounding the needle-stems in the endwise transferal of the needles from one bed or carrier to the other.
4. A knitting machine comprising two needle-beds or carriers disposed edge to edge with their needle-receiving grooves or tricks registering or alining, knitting cams in conjunction with the respective beds or carriers, double-ended needles occupying the said grooves or tricks and having cam-butts or heels which are engaged by the knitting cams of the bed or carrier for the time being containing them and actuated thereby to knit, cams and jacks for moving the said needles from one bed or carrier to the other and out of the range of action of one set of knitting cams into that of the other set, and means for lifting over the said butts or heels, to permit the needles to transfer from one bed or carrier to the other knitting loops surrounding the needle-stems at time of transfer.
5. A knitting machine comprising two needle-beds or carriers disposed edge to edge with their needle-receiving grooves or tricks registering or alining, knitting cams in conjunction with the respective beds or carriers, double-ended needles occupying the said grooves or tricks and having cam-butts or heels which are engaged by the knitting cams of the bed or carrier for the time being containing them and actuated thereby to knit, cams and jacks for moving the said needles from one bed or carrier to the other and out of the range of action of one set of knitting cams into that of the other set, and latches movably combined with the needles for lifting over the said butts or heels, to permit the needles to transfer from one bed or carrier to the other knitting loops surrounding the needle-stems at time of transfer.
6. A knitting machine comprising two needle-beds or carriers disposed edge to edge with their needle-receiving grooves or tricks registering or alining, knitting cams in conjunction with the respective beds or carriers, double-ended needles occupying the said grooves or tricks and having cam-butts or heels which are engaged by the knitting cams of the bed or carrier for the time being containing them and actuated thereby to knit, cams and jacks for moving the said needles from one bed or carrier to the other and out of the range of action of one set of knitting cams into that of the other set, and latches hinged to the said needles and adapted to swing into position to guide over the said butts or heels knitting loops surrounding the needle-stems in the endwise transferal of the needles from one bed or carrier to the other.
7. A rib-knitting machine comprising two needle-beds or carriers disposed edge to edge with their needle-receiving grooves or tricks registering or alining, knitting cams in conjunction with the respective beds or carriers, double-ended needles working in certain of the said grooves or tricks and having cam-butts or heels which are engaged by the knitting cams of the bed or carrier which for the time being contains them and actuated thereby to knit, single-ended

- needles in one bed or carrier alternating with the double-ended ones in the order of arrangement, cams and jacks for moving the double-ended needles from the bed or carrier primarily containing them to that containing the single-ended needles and out of the range of action of one set of knitting cams into 70 that of the other set, and also for reversely transferring them, movable latches by which knitting loops surrounding the stems of the double-ended needles are lifted over the heels or butts of the latter at the time of 75 the transfer of such needles from one bed or carrier to the other, selective butts or heels in connection with certain of the single-ended needles and also with the jacks of their bed or carrier for certain of the double-ended needles, and a selective cam in connection with such bed or carrier for coaction 80 with said selective butts or heels in moving the corresponding needles out of working relations with the knitting cams of such bed or carrier.
8. A rib-knitting machine comprising two 20 needle-beds or carriers disposed edge to edge with their needle-receiving grooves or tricks registering or alining, knitting cams in conjunction with the respective beds or carriers, double-ended needles working in certain of the said grooves or tricks and having cam-butts or heels which are engaged by the knitting cams of the bed or carrier which for the time being contains them and actuated thereby to knit, single-ended 25 needles in one bed or carrier alternating with the double-ended ones in the order of arrangement, cams and jacks for moving the double-ended needles from the bed or carrier primarily containing them to that containing the single-ended needles and out of the range of action of one set of knitting cams into 30 that of the other set, and also for reversely transferring them, means by which knitting loops surrounding the stems 35 of the double-ended needles are lifted over the heels or butts of the latter at the time of the transfer of such needles from one bed or carrier to the other, selective butts or heels in connection with certain of the single-ended needles and also with the jacks of their bed or carrier for certain of the double-ended needles, and a selective cam in connection with such bed or carrier for coaction 40 with said selective butts or heels in moving the corresponding needles out of working relations with the knitting cams of such bed or carrier.
9. A rib-knitting machine comprising two 45 needle-beds or carriers disposed edge to edge with their needle-receiving grooves or tricks registering or alining, knitting cams in conjunction with the respective beds or carriers, double-ended needles working in certain of the said grooves or tricks and having cam-butts or heels which are engaged by the knitting cams of the bed or carrier which for the time being contains them and actuated thereby to knit, single-ended needles in one bed or carrier alternating with the 50 double-ended ones in the order of arrangement, cams and jacks for moving the double-ended needles from the bed or carrier primarily containing them to that containing the single-ended needles and out of the range of action of one set of knitting cams into 55 that of the other set, and also for reversely transferring them, movable latches by which knitting loops surrounding the stems of the double-ended needles are lifted over the heels or butts of the latter at the time of the transfer of such needles from one bed or carrier to the other, selective butts or heels in connection with certain of the single-ended needles and also with the jacks of their bed or carrier for certain of the double-ended needles, and a selective cam in connection with such bed or carrier for coaction 60 with said selective butts or heels in moving the corresponding needles out of working relations with the knitting cams of such bed or carrier.
10. A rib-knitting machine comprising two 65 needle-beds or carriers disposed edge to edge with their needle-receiving grooves or tricks registering or alining, knitting cams in conjunction with the respective beds or carriers, double-ended needles working in certain of the said grooves or tricks and having cam-butts or heels which are engaged by the knitting cams of the bed or carrier which for the time being contains them and actuated thereby to knit, single-ended needles in one bed or carrier alternating with the double-ended ones in the order of arrangement, cams and jacks for moving the double-ended needles from the bed or carrier primarily containing them to that containing the single-ended needles and out of the range of action of one set of knitting cams into 70 that of the other set, and also for reversely transferring them, movable latches by which knitting loops surrounding the stems of the double-ended needles are lifted over the heels or butts of the latter at the time of the transfer of such needles from one bed or carrier to the other, selective butts or heels in connection with certain of the single-ended needles and also with the jacks of their bed or carrier for certain of the double-ended needles, and a selective cam in connection with such bed or carrier for coaction 75 with said selective butts or heels in moving the corresponding needles out of working relations with the knitting cams of such bed or carrier.
11. A knitting machine comprising two 80 needle-beds or carriers disposed edge to edge, cams in connection with each bed or carrier for actuating the needles therein to 85 knit, double-ended needles transferable from one bed or carrier to the other and having cam-butts or heels adapted to be engaged by the cams in connection with the respective beds or carriers, and means by 90

which knitting loops which surround needles withdrawn from one bed or carrier and transferred to the other thereof are lifted over the butts or heels of such needles.

5 12. A knitting machine comprising two needle-beds or carriers disposed edge to edge, cams in connection with each bed or carrier for actuating the needles therein to knit, double-ended needles transferable 10 from one bed or carrier to the other and having cam-butts or heels adapted to be engaged by the cams in connection with the respective beds or carriers, and movable latches by which knitting loops which surround needles withdrawn from one bed or carrier and transferred to the other thereof are lifted over the butts or heels of such needles.

13. A knitting machine comprising two 20 needle-beds or carriers disposed edge to edge, cams in connection with each bed or carrier for actuating the needles therein to knit, double-ended needles transferable from one bed or carrier to the other and 25 having cam-butts or heels adapted to be engaged by the cams in connection with the

respective beds or carriers, and hinged latches by which knitting loops which surround needles withdrawn from one bed or carrier and transferred to the other thereof are lifted over the butts or heels of such needles. 30

14. A double-ended knitting machine needle having a cam-but or heel intermediate its ends, and a hinged latch cooperating with said butt or heel to expand a knitting loop encompassing the needle-stem to enable the butt or heel to pass therethrough. 35

15. A double-ended knitting machine needle having a cam-but or heel intermediate its ends, and a movable loop-lifter 40 operating with said butt or heel to expand a knitting loop encompassing the needle-stem so as to enable the butt or heel to pass therethrough. 45

In testimony whereof I affix my signature in presence of two witnesses.
